UNITED STATES PATENT OFFICE

HOWARD J. KERR, OF WESTFIELD, NEW JERSEY, ASSIGNOR TO THE BABCOCK & WILCOX COMPANY, OF BAYONNE, NEW JERSEY, A CORPORATION OF NEW JERSEY

BAFFLE SUPPORT

Application filed June 8, 1929. Serial No. 369,473.

This application is a continuation in part of my copending application Serial No. 82,657.

This invention relates to a device for supporting baffles between vertically disposed tubes and by means of the tubes, so as to prevent the same from slipping longitudinally of the tubes. The invention will be understood from the description in connection with the accompanying drawings, in which:

Fig. 1 is a vertical section through a boiler illustrating an application of the invention.

Fig. 2 is a fragmentary elevation of a tube showing a preferred form for supporting the baffle thereon.

Fig. 3 is a view taken at right angles to Fig. 2, but with the baffle removed.

Figs. 4 and 5 are views taken on the lines 7-7 and 8-8 respectively, of Fig. 3.

In Fig. 1 is indicated a boiler of the Stirling type in which the mud drum is shown at 8, and the upper steam and water drums at 9, 10 and 11, the drums being connected by banks of tubes, as shown at 12, 13 and 14, and baffles are provided in the usual way. The two baffles 15 and 16, as shown in this figure, need to be supported to prevent the same from slipping downwardly, and supports made in accordance with my invention are shown therefor at 17.

The baffle support shown in Figs. 2 to 5 comprises a clamp 23 of U-shape, engaging a tube 13 and having a bolt 24 passing through the ends of the clamp which, in this illustration, is shown as a strap. Between the bolt and the tube is disposed a wedge 25 having a recess in one face to fit the tube, thereby providing extended thermal contact. A suitable thimble 26 may be placed around the bolt if desired.

Resting on the wedge 25 is a bearing member 27, here shown as an angle bar adapted to support the baffle 15. If desired, the bearing member may be independently held against the tube by means of a clamp 28 here shown as a U-shaped rod with ends on which are threaded nuts 29. If desired, the clamp 23 may be spot welded to the tube, as indicated at 30.

I claim:

1. In a boiler, a row of water tubes having a baffle disposed adjacent thereto, a clamp surrounding one of said tubes, a wedge between said clamp and tube, and a bearing member resting on said wedge and adapted to support said baffle thereon. 55

2. In a boiler, a row of water tubes having a baffle disposed adjacent thereto, a clamp surrounding one of said tubes, a wedge between said clamp and tube, a bearing member resting on said wedge and adapted to support said baffle thereon, and means to hold said bearing member against said tube. 60

3. In a boiler, a row of water tubes having a baffle disposed adjacent thereto, a U-shaped strap engaging one of said tubes, a bolt extending through the ends of said strap and adapted to tighten the strap on the tube, and a wedge disposed between the bolt and tube 70 and adapted to support said baffle, with the wedge face extending parallel to the length of the tubes. 65

4. In a boiler, a row of water tubes having a baffle disposed adjacent thereto, a U- 75 shaped strap engaging one of said tubes, a bolt extending through the ends of said strap and adapted to tighten the strap on the tube, a wedge disposed between the bolt and tube and adapted to support said baffle, and a bearing member disposed between said baffle and wedge. 80

5. In a boiler, a row of water tubes having a baffle disposed adjacent thereto, a U-shaped strap engaging one of said tubes, a bolt extending through the ends of said strap and adapted to tighten the strap on the tube, a wedge disposed between the bolt and tube and adapted to support said baffle, a bearing member disposed between said baffle and wedge, and means to clamp said bearing member against said tube. 85 90

HOWARD J. KERR.
